UNITED STATES PATENT OFFICE.

MAGNUS SMITH, OF WINNIPEG, CANADA.

FILM-HOLDER FOR PICTURE-EXHIBITING MACHINES.

No. 814,406.

Specification of Letters Patent.

Patented March 6, 1906.

Application filed May 1, 1905. Serial No. 258,301.

To all whom it may concern:

Be it known that I, MAGNUS SMITH, a subject of the King of Great Britain, and a resident of Winnipeg, in the Province of Manitoba and Dominion of Canada, have invented 5 a new and Improved Film-Holder for Picture-Exhibiting Machines, of which the following is a full, clear, and exact description.

The purpose of the invention is to provide 10 a film-holder for use in connection with picture-exhibiting machines, which will be simple, durable, economic, and readily operated and in which imperforate films can be used, thus simplifying the operation and greatly 15 adding to the lifetime of the films.

Another purpose of the invention is to provide 20 a construction whereby through one complete rotation of the main shaft certain grips or clutches are brought into play in order to draw the film down just the width of a 25 picture on the film to be exhibited and there to hold the film still while the first-named factor again ascends for another operation, all of which is accomplished during the mentioned single revolution of the main shaft.

The invention consists in the novel construction and combination of the several parts, as will be hereinafter fully set forth, and pointed out in the claims.

Reference is to be had to the accompanying 30 drawings, forming a part of this specification, in which similar characters of reference indicate corresponding parts in all the figures.

Figure 1 is a rear elevation of the improved 35 device, the gripping device for operating the films being in its highest position or in position to carry the film downward. Fig. 2 is a vertical section through the device, taken at one side of the center. Fig. 3 is a longitudinal center taken practically on the line 3 3 40 of Fig. 1, and Fig. 4 is a detail horizontal section illustrating the application of a spring to the lower or retaining gripper.

The device is essentially a film carrying and operating attachment to picture-exhibiting machines and may be applied to such machines in any convenient or desired manner.

In the construction of the machine a front or body plate A is employed, having an exposure or sight opening 10 therein and a lower opening 11, which is partially in the interest of lightness and partially to provide access to the film for adjusting the same to the 55 grippers, to be hereinafter described. Brackets 12 extend down from each side of the cen-

ter of the lower portion of the front or body plate A, projecting downwardly and rearwardly therefrom, and in said brackets, quite close to the front of the body-plate A, a guide-roller 13 is mounted to turn, while at the free ends of the brackets a shaft 14 is located, upon which shaft a reel 15 is mounted. The film 16 is wound upon this reel as said film passes from the exposure or sight opening 10, 60 and said shaft 14 is provided with a pulley 17, driven by a belt connection 17^a with a corresponding pulley 18 on the main or drive shaft 19. This main or drive shaft 19 crosses the lower portion of the lower opening 11 in 70 the front or body plate A, as is shown in Figs. 1 and 2, and is journaled in suitable bearings 20, secured to the rear of said plate. The shaft 19 may be turned by power, if desired, but, as illustrated, is rotated by a hand-wheel 75 21, secured to one end thereof.

The shaft 19 is provided with a fan-shaped cam 22, attached to its central portion and adapted as a lifting-cam, as shown in Figs. 1 and 2. Said shaft is further provided with a cam 23 at the left of its center and with a cam 24 at the right of its center, the cams 23 and 24 being formed by suitably reducing the diameter of the shaft 19, as is particularly shown in Fig. 1. The high point of one of 85 the said cams 23 and 24 is diametrically opposite to the corresponding point of the other, and in the normal position of the shaft 19 (shown in Fig. 1) the lift-cam 22 extends vertically upward, as does likewise the lower 90 point of the left-hand cam 23, while the high point of the right-hand cam 24 is uppermost at such time.

A suitable tightener 25 is provided for the belt 17^a, which tightener is hinged to the rear 95 of the front or body plate A and is held in engagement with the belt by a spring 26.

The film 16 is imperforate and is guided at the sight or exposure opening 10 in the body-plate A by a guide-plate 27, secured to the back of the body-plate and having an undercut forward face 28. The said guide-plate is provided with an opening 29, registering with the sight or exposure opening 10.

A slide 30 is located at the upper portion 100 of the slot 11, having movement upon the rear face of the body-plate A, which slide extends beyond the side walls of the opening 11 and is provided with side arms 31, which in in the upper position of the slide extends beyond the upper edge of the said opening. The side arms 31 of the slide 30 are bifur- 105 110 115

cated, so that one member of an arm is at the front and the other member is at the back of the body-plate, and the remaining portion of the said arms 31 at their outer edges 5 and the corresponding edges of the slide 30 are provided with grooves 32 to receive the side edges of the opening 11, as is shown by dotted lines in Fig. 1 and by positive lines in Fig. 3, and in the front central portion of the 10 slide 30 a recess 33 is made, extending from top to bottom, which recess is of slightly greater width than the width of the film 16, as is shown by Fig. 3. At the left-hand edge of the slide 30 knuckles 34 are formed, which 15 receive between them the knuckle 35 of a door 36, held normally closed at the right-hand edge of the slide by a latch 37 of any approved type.

A gripper B, preferably in the form of a 20 plate, is pivoted at its upper edge to the upper edge portion of the slide 30 at the back of said slide, suitable bearings 38 being provided for the purpose, and the said gripper is provided with forwardly-projecting ribs 39, 25 which extend through suitable openings in the slide 30 into its recess 33. The ribs 39 are preferably vertical and are tipped with rubber 40 or other soft material and are adapted by frictional engagement with the 30 film to hold the film at proper time tightly against the door 36, and such time is when the film is to be moved downward or a picture is to be shifted. A finger 41 is secured to the left-hand portion of the gripper B, 35 which finger extends from the said gripper B downward to an engagement with the cam 23 on the main or drive shaft 19, and at the lower edge of the slide 30 a horizontal projection 42 is formed. On this projection a 40 spring 43 is secured, having bearing against the rear face of the gripper B, as is shown in both Figs. 1 and 2, and a spring 44, preferably a coiled spring, is secured to the under face of the projection 42 and to the body- 45 plate A, preferably at a point near its lower end.

The action of the cam 23 is through the finger 41 to carry the lower or free portion of the gripper B either outward, so as to free the 50 film from the ribs 39, carried by the gripper, or to permit the spring 43 to act to force the said ribs 39 to gripping engagement with the film. The slide 30 is forced upward by the lifting-cam 22 engaging with the projection 55 42, and as the shaft 19 is turned the said lift-cam permits the slide to drop, it being drawn downward by the action of the spring 44.

A supporting-plate 45 is firmly secured to the rear of the body-plate A at the lower portion of the slot 11, as is shown in Figs. 1 and 2, and the lower edge of the lower gripper B' is pivoted on the said fixed plate 45, suitable bearings 46 being provided for that purpose.

At the upper or free end of the lower gripper 65 B' a finger 47 is secured, which is carried

rearward and downward to an engagement with the cam 24. The rear face of the fixed plate 45 is provided with a recess 48, corresponding to the recess 33 in the slide 30, the recess 48 being for the same purpose. A 70 door 49, corresponding to the door 36 used in connection with the upper gripper B, is provided for the lower gripper B', the said door, however, being hinged at one edge to the left-hand side of the body-plate A at the 75 front at the lower portion of the opening 11, as is indicated in Fig. 4, the opposite or right-hand edge of the door 49 being provided with a suitable latch for engagement with the right-hand portion of the body-plate, so that the 80 film in its passage is carried down through the recess 48 in the lower fixed plate 45. The lower gripper B' is provided with ribs 50, which pass through suitable openings in the fixed plate 45 into the recess 48, as is shown 85 in Fig. 2, and said ribs 50 act upon the film 16 in the same manner as has been described with reference to the ribs of the upper gripper B.

When the finger 47 of the gripper B' engages with the high point of the cam 24, the gripper B' is carried outward to release the film from engagement with the ribs 50; but when the said finger 47 engages with the low point of the cam 24 the ribs 50 of the lower 95 gripper B' engage with the said film and serve to hold it stationary while the slide 30 is being carried upward through the upward movement of the lift-cam 22. The lower gripper B' is forced to move outward to a 100 gripping position relative to the film through the medium of a spring 51, (shown particularly in Fig. 4,) which spring is secured to one side portion of the fixed plate 45 and has bearing against the corresponding edge portion of the lower gripper B'. 105

The film is passed down through the space between the guide-plate 27 and the body-plate A, crossing the exposure-openings 10 and 29, as is shown in both Figs. 1 and 2, and the doors 36 and 49 are then opened and the film is adjusted to the ribs of the upper and the lower grippers B and B', and then the doors are closed. Finally, the film is carried over the guide-roller 13 at the bottom of the device and attached in any suitable or approved manner to the reel 15. 110

In operation, the parts being in the position shown in Fig. 1, by turning the shaft one revolution the following action takes place: 115 The finger 41 will at such time be in engagement with the low point of the cam 23, and consequently the ribs 39 of the upper gripper B will be in engagement with the film, as is shown in Fig. 3. As the shaft revolves and 120 the lift-cam 22 descends the spring 42 acts to draw the slide 30 downward, and just about the time that the lift-cam 22 is again about to engage with the projection 42 of the slide to raise it the complete picture will have been 125 130

displayed at the exposure-opening, and then the low point of the cam 24 will be engaged by the finger 47 of the lower gripper B' and the said gripper will be forced by its spring 51 to an engagement with the film, holding the film stationary, while at the same time the high point of the cam 23 will be engaged by the finger 41 of the upper gripper B and said gripper will be taken out of frictional engagement with the film, permitting the slide 30 to be carried upward, while the lower gripper B' prevents the film from moving at that time. When the slide has reached the extent of its upward movement, the low point of the cam 23 will be in engagement with the finger 41 of the upper gripper B, causing it to be brought in engagement with the film, and the high point of the cam 24 will be in engagement with the finger 47 of the lower gripper B', carrying the said gripper out of engagement with the film and permitting the film as it is carried down by the next downward movement of the slide to be properly wound up on the reel 15.

Having thus described my invention, I claim as new and desire to secure by Letters Patent—

1. In film-holders for picture-exhibiting machines, a body-plate having an exposure-opening therein, a guide for the film back of the said opening, a main shaft, a sliding gripper above the main shaft, a fixed gripper below said shaft, both grippers being in the path of the film, and means operated by the shaft for alternately carrying one gripper to gripping position and for releasing the other gripper.

2. In film-holders for picture-exhibiting machines, a body-plate having an exposure-opening therein, a guide for the film back of the said opening, a main shaft, a sliding gripper above the main shaft, a fixed gripper below said shaft, both grippers being in the path of the film, means operated by the shaft for alternately carrying one gripper to gripping position and for releasing the other gripper, and a device also carried by the shaft for controlling the sliding movement of the sliding gripper.

3. In a film-holder for picture-exhibiting machines, a body-plate, an imperforate film, guards for the same, a main shaft, a gripper mounted for pivotal and a sliding movement, a gripper below the shaft having pivotal movement only, both grippers being located in the path of the film, a lifting-cam for the upper gripper controlled by the said shaft, cams forming portions of the shaft, having their highest points facing in opposite directions, fingers connected with the grippers in engagement with the shaft-cams, whereby when one gripper opens the other closes, and a reeling device for the film also operated from the same shaft.

4. In film-holders for picture-exhibiting machines, a body-plate having an exposure-opening therein and an opening below the exposure-opening, an imperforate film which crosses the two openings in the body-plate, a guide for the film at the exposure-opening, a spring-controlled slide having movement at the upper portion of the lower opening, a gripper pivoted on the said slide, having ribs which extend through openings in the slide, a spring arranged to normally hold the said gripper closed, a drive-shaft below the said frame, a supporting-plate crossing the lower opening at its lower portion, a second gripper located below the said shaft, being pivoted on said supporting-plate, said second gripper having a spring which normally closes it, and ribs upon the said second gripper which pass through its supporting-plate, a door carried by the slide, being arranged opposite the gripper thereon, a second door carried by the body-plate, being opposite the second or lower gripper, and means substantially as described for raising and lowering the said slide and opening and closing the gripper carried thereby, and means also operated from the said shaft, for opening and closing the lower gripper alternately with the upper one, the said film being passed across the exposure-opening and between the grippers and the said doors.

5. In a film-holder for picture-exhibiting machines, a body-plate having an exposure-opening therein and a second opening below the exposure-opening, a slide mounted upon the body-plate at the rear and at the upper portion of the lower opening therein, a gripper carried by the said slide, a projection extending from the slide and a spring connected with the projection and the said body-plate, a shaft located below the said slide, a fan-shaped cam secured to the said shaft and arranged for engagement with the projection from the slide, a cam formed in the shaft at each side of the fan-shaped cam, the latter cams having their highest points facing in opposite directions, a support crossing the lower portion of the lower opening in the body-plate, a second gripper pivoted on said support, tension devices for both grippers, and fingers extending from the grippers, which fingers engage with the cams on said shaft, the grippers being adapted for alternately opening and closing movement relative to the film passed over the exposure-opening, as described.

In testimony whereof I have signed my name to this specification in the presence of two subscribing witnesses.

MAGNUS SMITH.
